UNITED STATES PATENT OFFICE

2,262,812

CANNED LIQUID DISPENSER

Ray L. Morehouse and John K. Gumpfer,
Chicago, Ill.

Application February 17, 1940, Serial No. 319,522

11 Claims. (Cl. 65—61)

This invention relates to canned liquid dispensers, and its principal object is to provide novel means for enclosing a tin can, opening it and serving the contents directly from the can.

Condensed milk, cream, vegetable juices and many other liquids which are, in most instances, packaged in tin cans, are sometimes dispensed directly from the cans through punctures made therein. Tin cans, containing condensed milk, cream or other wholesome liquids are unsightly when used on the table, and are not entirely sanitary after they have once been opened, and one object of the present invention is the provision of an attractive and ornamental device for enclosing the tin can and having means whereby communication is established between the interior of the can and the spout of the dispenser, whereby the contents may be served directly from the tin can.

Another object is to provide a shell or housing adapted to receive an unpunctured, filled tin can and provided with one or more blades whereby the tin can is opened at a place registering with the spout, whereby the contents may be dispensed directly from the tin can.

Another object is to provide means for securing the can in the shell or housing while it is being opened, and thereafter until the can is to be ejected from the shell.

Another object is to provide means for ejecting the empty can from the dispenser.

Other objects and advantages will appear in the course of this specification, and with said objects and advantages in view, this invention consists in the several novel features herein-after fully set forth and claimed.

One embodiment of the invention is illustrated in the drawing accompanying this specification, in which

Fig. 1 is a side elevation of the dispenser, certain parts being shown by dotted lines in a second position.

Fig. 2 is a plan of the dispenser.

Fig. 3 is a vertical longitudinal section taken on the line 3—3 of Fig. 2.

Fig. 4 is a horizontal section taken on the line 4—4 of Fig. 3.

Fig. 5 is a detail vertical cross section taken on the line 5—5 of Fig. 1, and

Fig. 6 is a detail vertical cross section taken on the line 6—6 of Fig. 1.

Referring to said drawing, the reference character 10 designates a shell or housing having a somewhat bell shape and formed with a top wall 11 from which a cylindrical side wall 12 projects

down and flares outward adjacent its lower end to provide an enlargement or base 13. The internal diameter of the cylindrical wall 12 is slightly greater than the external diameter of the tin can 14 with which the dispenser is used. The device may be made in various sizes to accommodate it to various sizes of tin cans.

Rotatively mounted upon the top wall 11 is a spout 15 which, as shown, is provided with a tubular, externally threaded neck 16 that extends through an opening in the top wall 11, and above said neck the spout is formed with a flange 17 to provide a shoulder of greater diameter than the opening in the top wall 11. A circular, notched nut 18, threadedly secured on the neck 16, is provided for mounting the spout upon the top wall 11. Said nut 18 is provided with a reduced upper part 19 which fits the hole in the top wall 11. The reduced part of the nut is slightly wider than the thickness of the top wall, so that when it is screwed up tight on the neck 18 it bears against the under side of the flange 17 and permits the spout to be freely turned in the opening in the top wall.

Secured to and projecting down from the lower edge of the neck 16 is one or more pointed, sharp blades 20, which are adapted to be thrust through the top wall of the can and to cut a circular disc therefrom, thereby providing an opening communicating with the spout 15 through the neck 16.

In the upper end of the shell or housing is secured a rubber or other resilient pad 22 which is formed with an opening to receive the neck 16 and nut 18. The lower face of the pad may be provided with a series of annular ribs 23, and it is provided with an annular rib 24 which surrounds the neck 16 of the nozzle. If desired, a cavity 22a may be provided in the upper face 40 of the pad, in which a partial vacuum may be created by pressing up on the pad, this serving to more effectively hold the pad in place in the upper end of the shell or housing.

Welded or otherwise secured to and projecting from the spout 15 is an arm 25, desirably of channel like formation and extending to a place somewhat beyond the side of the shell or housing. Disposed between the upstanding sides of the arm 25, and pivotally mounted on said arm 50 as by a rivet 26, is the stem 27, of a lid or cover 28, for closing the spout. The stem 27 is formed upon its outer end with a thumb piece 29 by which the lid may be lifted by depressing the thumb piece. A coiled spring 30 interposed between the stem 27 and the cross wall of the arm

25 serves to yieldingly hold the lid down on the spout.

Welded or otherwise secured to the cylindrical wall 12 of the shell are two spaced ears 31, which desirably are spaced the same distance apart as the upright sides of the arm 25, and between said ears is pivotally mounted, as by a pin or rivet 32, a combined can lock and ejector 33, which is provided upon its outer end with a handle 34, by which the device may be handled when dispensing the contents of the can. The combined can lock and ejector is formed on one edge with a heel 35 which is adapted to be projected through a slot 36 formed in the wall 12 of the shell, and thereby indent the can wall as is seen at 37, in Fig. 3. Above the heel 35 the combined lock and ejector is formed with a foot 38, which in the operative position of the device engages with the top edge portion of the tin can. Projecting down from the pin or rivet 32, is a tail piece 39, which in one position of the combined can lock and ejector engages with the cylindrical wall 12, and serves as a stop to hold the combined can lock and ejector in locked position. A spring 40 interposed between the wall 12 of the shell and the tail piece 39 serves to swing the combined can lock and ejector into the dotted line position indicated in Fig. 1, which is the position occupied by the parts when a can is to be inserted into the shell. If desired, a supplemental locking means 42 may be provided which may be in the nature of a flat-headed screw threadedly mounted in the combined can lock and ejector, and adapted to be forced against a tin can and to slightly indent its wall in order to positively lock it in place in the shell.

Means are provided for locking the arm 25 and spout 15 in their operative position and as shown said means comprise a lug 41 which is struck up from the cross wall of the arm and is adapted to engage the inner faces of the ears 31 to prevent the arm 20 from being accidentally displaced.

In Fig. 1, two positions of the tin can are shown; 14a, 14b indicating the top and bottom of the can when partially inserted into the shell, and 14c, 14d indicating the top and bottom of the can when it is fully inserted.

In the operation of the device the handle 25 is swung to one side of its operative position, namely, to one side of that shown in Fig. 2, whereupon the spring 40 turns the combined can lock and ejector into the dotted line position indicated in Fig. 1. A filled can is then inserted into the shell or housing 10, its top, when in the position indicated at 14a in Fig. 1, engaging the ejector foot 38. The shell is then pressed down upon the can until the latter is firmly pressed against the pad 22. As the device is pressed down the blades puncture the can top and the foot 38 is swung upward from the dotted line position seen in Fig. 1 to the position seen in solid line in Fig. 3, and as a result the heel 35 is forced against the wall of the can, thereby indenting it and positively locking it in the shell. The arm 25 is thereupon swung around upon the axis of rotation of the neck 16, thereby forcing the blades 20 through the can top, and cutting out a circular disc therefrom. The arm is then returned to its operative position with the lug 41 engaging the ears 31 and with its adjacent end overlying the handle of the combined can lock and ejector and arranged to lock the same in place. The device may then be handled with

5 the handle 34, and its contents or parts thereof may be poured out through the spout by first raising the lid thereof. The rubber pad 22 provides a seal between the can and neck and prevents any leakage of the liquid at the neck.

10 When the contents of the can have been emptied therefrom, the arm 25 is swung to one side of its operative position, and the handle 34 is swung upward to the dotted line position shown in Fig. 1. As a result the foot 38 swings in a downward direction and forces the can downwards far enough for a person to grasp it and withdraw it from the shell.

15 We claim as new and desire to secure by Letters Patent:

20 1. A canned liquid dispenser comprising a can-holder adapted to receive a can from which the contents are to be dispensed, said holder having a spout through which the canned contents are dispensed, rotatable can-opening means carried by the spout for cutting a circular opening in the can in register with the spout, said spout and can-opening means being rotatably mounted on the can holder about a vertical axis, an actuating arm carried by the spout for rotating said can-opening means, and can locking means pivotally mounted on said can holder and arranged to be held in locking engagement with the can by said actuating arm.

25 2. A canned liquid dispenser comprising a shell, closed at the top and open at the bottom, and adapted to receive a can from which the contents are to be dispensed, a spout rotatively mounted on the shell, rotative cutting means rigid with said spout for cutting an opening in the can in register with the spout, an actuating arm for rotating said spout and cutting means, a can lock pivotally carried by the shell, and a handle secured to said can lock, said actuating arm having a part normally overlying the handle of the can lock and arranged to lock the same in place.

30 3. A canned liquid dispenser comprising a shell, closed at the top and open at the bottom, and adapted to receive a can from which the contents are to be dispensed, a spout rotatively mounted on the top of the shell, cutting means rigid with said spout for cutting an opening in the can in register with the spout, an actuating arm for rotating the spout and cutting means, and a combined can lock and ejector pivotally carried by the shell and having a foot and a heel, the foot being arranged to be engaged and partially rotated by a can when being inserted into the shell, whereby to force the heel into locking engagement with the can, and the actuating arm being arranged to overlie the handle of the combined lock and ejector and lock the same in place.

35 4. A canned liquid dispenser comprising a shell having a top and open at its bottom, and adapted to receive a can from which the contents are to be dispensed, a spout rotatably mounted about a vertical axis on the top of the shell and having an actuating arm, can-cutting means carried by said spout and arranged to puncture the can top when the can is fully inserted into the shell, said arm serving as means whereby to rotate the spout and therewith the cutting means to cut a disc out of the can top, and means to lock said actuating arm and therewith the spout in the pouring position of the spout.

40 5. A canned liquid dispenser comprising a shell having a top and open at its bottom, and adapted to receive a can from which the contents

are to be dispensed, a spout rotatably mounted about a vertical axis on the top of the shell, and having an actuating arm, can-cutting means carried by said spout and arranged to puncture the can top when the can is fully inserted into the shell, said arm serving as means whereby to rotate the spout and therewith the cutting means to cut a disc out of the can top, a pair of ears projecting from the shell and serving to lock the arm and therewith the spout in the pouring position of the spout, and a combined can lock and ejector pivotally mounted on the ears and having a handle whereby it is manipulated, and said actuating arm serving, when in operative position, to lock the handle against movement relative to the can.

6. A canned liquid dispenser comprising a shell having a top and open at its bottom, and adapted to receive a can from which the contents are to be dispensed, a spout rotatably mounted on the top of the shell and having an actuating arm, can-cutting means carried by said spout and arranged to puncture the can top when the can is fully inserted into the shell, said arm serving as means whereby to rotate the spout and therewith the cutting means to cut a disc out of the can top, ears projecting from said shell and serving to lock the arm and therewith the spout in the pouring position of the spout, and a combined can lock and ejector pivotally carried by the ears and having a foot adapted to be engaged by a can top when the can is inserted into the shell, whereby to partially rotate the combined lock and ejector and therewith project the heel into locking engagement with the can.

7. A canned liquid dispenser comprising a shell closed at the top and open at the bottom and adapted to receive a can from which the contents are to be dispensed, a spout having a neck protruding inwards through the top of the shell, means to rotatably mount the spout on the top of the shell, cutting means carried by said neck in position to puncture a can when the latter is inserted into the shell, an actuating arm secured to and projecting from the spout, whereby the spout may be rotated, said arms having a downwardly projecting lug, ears projecting from the shell in position to engage said lug between them, whereby to lock the actuating arm and therewith the spout in the pouring position of the spout, and a combined can lock and ejector pivotally carried by the ears.

8. A canned liquid dispenser comprising a shell closed at the top and open at the bottom, and adapted to receive a can from which the contents are to be dispensed, a sealing pad secured

5 within the shell against the top thereof, a spout rotatably mounted on the top of the shell and having a neck extending through an opening in the pad, cutting means carried by the neck and adapted to puncture a can when inserted into the shell against the pad, an actuating arm whereby the spout is rotated and a swinging can lock for locking the can in the shell, having a can ejector arranged to be engaged by the top of a can while being inserted into the shell, whereby the can lock is moved into locking engagement with the can.

9. A canned liquid dispenser comprising a shell adapted to receive a can from which the contents are to be dispensed, a spout through which the canned contents are dispensed, said spout being rotatably mounted on the shell on a vertical axis and having a channeled arm whereby the spout is rotated, can-opening means carried by the spout for cutting an opening in the can in register with the spout, a lid for said spout having a stem extending through the channel of said arm and pivotally mounted on the sides of the arm.

10. A canned liquid dispenser comprising a shell adapted to receive a can from which the contents are to be dispensed, said shell having a spout rotatably mounted thereon and through which the can contents are dispensed, can opening means carried by said spout for cutting an opening in the can in register with the spout, an arm projecting from the spout by means of which it is rotated, a combined can lock and ejector pivotally carried by the shell and having a handle by means of which it is manipulated, and means to lock the arm in position over said combined can lock and ejector.

11. A canned liquid dispenser comprising a shell adapted to receive a can from which the contents are to be dispensed, said shell having a spout rotatably mounted thereon and through which the can contents are dispensed, can opening means carried by said spout for cutting an opening in the can in register with the spout, an arm projecting from the spout by means of which it is rotated, a combined can lock and ejector pivotally carried by the shell and having a handle by means of which it is manipulated, means to lock the arm in position over said combined can lock and ejector, and a spring engaging said combined can lock and ejector and adapted to yieldingly hold the same in position to be acted upon by a can when inserted into the shell.

RAY I. MOREHOUSE.
JOHN K. GUMPPER.
